COLLAPSIBLE CHAMBER PUMP WITH
ROTARY COMPRESS

Henry J. Rand, Bratenahl, Ohio, assignor to Flexible Pumps, Inc., Bratenahl, Ohio, a corporation of Ohio

Application September 2, 1948, Serial No. 47,395

3 Claims. (Cl. 103—149)

1

This invention relates to improvements in a pump of the type which uses a diaphragm as the fluid driving element.

An object of the invention is to provide a pump having a diaphragm adapted to be intermittently seated in a registering annular groove, by rotatable abutment means such as cams or rollers passing over the diaphragm whereby to provide suction and discharge at a properly arranged fluid inlet and outlet.

Another object of the present invention is to provide a novel and improved pump with a flexible diaphragm which cooperates with a mating groove and rotatable abutment means to produce a pumping action.

Other objects of the invention include the provision of annular pumping chamber grooves of various cross-sectional shape to produce the results desired, various cooperating diaphragm shapes, various types of partition means to separate the fluid inlet and outlet, various means for progressively causing the diaphragm to press into the annular groove in a pumping cycle, means for reducing friction and abrasion and other improvements as will appear as the description proceeds.

Other objects and advantages of the present invention will be apparent from the accompanying drawings and specification and the essential features thereof will be set forth in the appended claims.

In the drawings,

Fig. 1 is a central vertical sectional view on the line 1—1 of Fig. 2;

Fig. 2 is a sectional view on the line 2—2 of Fig. 1;

Fig. 3 is a sectional view on the line 3—3 of Fig. 1;

Fig. 4 is a sectional view on the line 4—4 of Fig. 1;

Fig. 5 is a central vertical sectional view similar to Fig. 1 showing a modification;

Fig. 6 is a central vertical sectional view on the line 6—6 of Fig. 7 showing another modification;

Fig. 7 is a side elevational view from the right of Fig. 6;

Fig. 8 is a sectional view on the line 8—8 of Fig. 6; while

Fig. 9 is a central vertical sectional view similar to Figs. 1, 5, and 6, but showing another modification;

Fig. 10 is a modification of Fig. 4 showing the partition carried by the pump body.

Referring first to Figs. 1 to 4, I have shown a pump body 10 which carries a diaphragm 11. The periphery 11a of diaphragm 11 is securely

2

clamped to the pump body 10 by the clamping ring 12, the ring 12 being secured to the pump body by bolts (not shown).

A shaft 13 is mounted for rotational movement in the pump body 10 in a suitable bushing 14, while bearing 15 takes end thrust. Mounted on shaft 13 for rotational movement therewith is a cam arm 16 which carries rotatable abutment means such as the cams 17 and 18 on its outer ends.

The central portion 11b of the diaphragm 11 is securely clamped to the pump body 10 by the clamping block 19, secured by bolts or screws not shown. Intermediate the periphery 11a and the central portion 11b of the diaphragm 11 is an annular projection 11c of generally rectangular cross section and which is molded integral with the diaphragm 11, the projection 11c and the walls of the annular groove 10a defining a pump chamber 10b. The projection 11c is adapted to reciprocate (under the influence of cams 17 and 18) in an annular groove 10a in the pump body 10 to produce a pumping action.

A seal or partition means for directing the pump chamber is provided at all times between the fluid inlet 20 and the fluid discharge 21 by an enlarged portion 11d of the annular projection 11a which is interposed between the inlet 20 and the discharge 21. The enlarged portion 11d extends below the annular groove 10a and radially inwardly and outwardly of the groove 10a, as shown in Figs. 1, 3, and 4.

It will now be apparent that as the shaft 13 is rotated in the direction of the arrow of Fig. 2, carrying with it the cams 17 and 18, the projection 11c is forced to the bottom of the annular groove 10a by the cams 17 and 18. The diaphragm 11 is of rubber-like material so as to provide considerable resilience and flexibility as illustrated in Fig. 4. The stable position of the diaphragm lifts it away from the groove 10a. It will also be apparent that as the cam 17 or 18 passes the discharge outlet 21 it will force the fluid out of the annular groove 10a and through the discharge 21.

As a cam passes over the diaphragm and groove, pushing the liquid ahead of the cam, the projection 11c rises after the cam has passed creating a suction causing inward float at inlet 20.

A flexible wear plate 22 may be interposed between the cams 17 and 18 and the diaphragm 11 to reduce friction and prevent wear of the diaphragm.

The annular flange 19a on the clamping block 19 overlies the diaphragm 11 to prevent the bead 11c from being blown out of the groove 10a by an

excess of pressure. In other words, when the diaphragm engages 19a, the bead 11c is still in the groove 10a.

A cap 23 is threaded on an extension 12a of the clamping ring 12 to provide an oil chamber 24 to properly lubricate the moving parts.

In the modification of Fig. 5, I have shown rollers 30 (only one being shown) replacing the cams 17 and 18 of Figs. 1 to 4. I have omitted the wear plate 22 of Figs. 1 to 4, although it will be obvious that the wear plate may also be used when using rollers 30.

Note that the thickness of roller 30, radially of the annular groove, is less than the width of the groove. This is for the purpose of more nearly equalizing the path of travel of the radially inner and outer edges of the roller. Otherwise the device of Fig. 5 pumps like the device of Fig. 1, and like parts have been given like reference numbers.

In Figs. 6 to 8, I have shown a generally V-shaped groove 35, having slightly convex sides 35a, as I find the convex sides provide a better seal than do flat sides. The diaphragm 36 has a generally V-shaped annular portion 36a which registers with and coacts with the groove 35, while the rollers 37 also have V-shaped surfaces to conform to the upper face of diaphragm 36 when it is pressed in toward the groove. It will be noted in Fig. 6 that the groove has a rounded apex where the reference character 35 is applied; and the registering portion of the diaphragm has an apex, where the reference character 36a is applied, more acute than the apex of the groove. Clamping rings 38 and 39 securely hold the diaphragm to the pump body and a seal is provided between the fluid inlet 40 and fluid discharge 41 by the enlarged portion 36b of the diaphragm 36 similar in all respects to the enlarged portion 11d shown in Fig. 1. Other parts like Fig. 1 are given similar reference numbers.

In Fig. 9, is shown a further modification wherein a flat diaphragm 42 is provided over an annular pump chamber groove 43 which is V-shape in section. One or more rotatable rollers 44 formed to press the diaphragm to the bottom of the groove, provide a pumping action similar to those previously described.

In Fig. 10, the partition means 45 between the fluid inlet and outlet is shown mounted in the pump body instead of being carried by the diaphragm. A spring 46 urges the partition into engagement with the diaphragm so that it always seals.

I claim:

1. In a pump of the character described, a pump body, an annular groove in one face of said body, a flexible diaphragm mounted on said body over said groove, said diaphragm and said groove walls defining a pump chamber, said groove being

substantially V-shape in cross-section, said diaphragm having a V-shape annular projection adapted to fit into said groove but normally spaced from said groove, rotatable abutment means engaging said diaphragm over a limited area to press a portion of said diaphragm into said groove, means for rotating said abutment means in a path approximately registering with said groove, a fluid inlet to said groove, a fluid outlet from said groove, and partition means dividing said pump chamber between said inlet and said outlet.

2. In a pump of the character described, a pump body, an annular groove in one face of said body, a flexible diaphragm mounted on said body over said groove, said diaphragm and said groove walls defining a pump chamber, said groove being substantially V-shape in cross-section and having a rounded apex, said diaphragm having an annular portion registering with said groove, said portion being of V-shape section whose surfaces diverge at approximately the same angle as the walls of the groove and the apex of said diaphragm V-shape section being more acute than the apex of the groove section, the apex of said diaphragm section being annular in form and adapted to fit into said groove but normally spaced from said groove, rotatable abutment means engaging said diaphragm over a limited area to press a portion of said diaphragm into said groove, means for rotating said abutment means in a path approximately registering with said groove, a fluid inlet to said groove, a fluid outlet from said groove, and partition means dividing said pump chamber between said inlet and said outlet.

3. The combination of claim 1 wherein said partition means is carried by said diaphragm, there being a recess in said body receiving said partition means, and the mutually engaging portions of said partition means and of said recess being of sufficient depth to remain in contact during movement of the V-shape annular projection of said diaphragm into and out of said groove.

HENRY J. RAND.
